UNITED STATES PATENT OFFICE.

DAVID ROBINSON, OF CLEVELAND, AND RUSSELL J. WITTMER, OF EAST CLEVELAND, OHIO, ASSIGNORS TO NATIONAL MALLEABLE AND STEEL CASTINGS COMPANY, OF CLEVELAND, OHIO, A CORPORATION OF OHIO.

CAR COUPLER.

Application filed August 5, 1926. Serial No. 127,230.

Fig. 1 is a side elevation of a car coupler embodying our invention and showing in dotted lines the lock and operating parts in locked or lowermost position; Fig. 2 is also a side elevation, but showing in dotted lines the lock driven rearwardly under impact coupling against a preliminary stop; Fig. 3 is likewise a side elevation of the coupler, but with the lock in lock-set position; Fig. 10 4 is a plan with the lock in lock-set position and showing in outline an intercoupled coupler of like character; Fig. 5 is likewise an elevation, but showing the lock about to return from lock-set to lowermost position; Fig. 15 6 is a side elevation of the lock and the operating mechanism; Fig. 7 is an enlarged side elevation of the lock-set piece; and Fig. 8 is a front elevation thereof.

Our invention relates to a car coupler of 20 the rigid jawed type shown in Letters Patent No. 1,201,665 of John Willison, dated October 17, 1916, and comprises novel means for lock-setting the lock. Our invention also comprises various features which we 25 shall hereinafter describe and claim.

Referring to the drawings, the coupler head 2 has the usual buffing jaw 3, pulling jaw 4, and a cavity 5 extending rearwardly from the buffing and guiding face 6 into the 30 body of the coupler head. Within the cavity 5 are the operating parts, which comprise the lock 7, the operating lever 8, and the lock-set piece 9.

In assembling the coupler the lock-set piece 9 is first inserted into the cavity 5, and the elongated eye 10 of the piece is passed over the transversely extending pin 11, which is preferably integral with the coupler head in the upper central portion there- 35 of. Next, the lock throw or operating lever 8 is placed within the bottom cavity 12 of the lock with its trunnion 13 in the elongated transversely extending slot 14 of the lock 7, and lock and lever are inserted into 40 the cavity 5 with the lower arm 8^a of the lever 8 extending down through a slot in the bottom of the coupler head. The lock is held in position in the cavity 5 by its shoulder 15 and the lug 15^a, which engage 45 respectively the stops 16 and 16^a and limit the outward extent of its movement.

During the coupling operation, as the lock 7 is driven back by the impact of an opposing coupler the rear end of the arm 8^b of the lever 8 strikes the projection 17, in 55 the manner shown in Fig. 2. This preliminary stop 17 causes a rapid return of the lock under impact coupling and prevents the lock from being accidentally thrown into lock-set position during coupling operations.

To place the lock in lock-set position the lever 8 is rotated by a rearward pull on the arm 8^a (by means not shown), so that the upper end 8^b of the lever 8 is rotated above 65 the preliminary stop 17 and this permits the lock to be pulled rearwardly by the lever 8. The rearward and upward movement of the lock in its cavity causes the lock shoulder 20 to come into contact with the projection 9^a 70 of the lock-set piece 9 and thereby lift the piece vertically. When the lock has been pulled clear back so that its shoulder 20 has passed under and is disengaged from the projection 9^a and that projection has 75 dropped into the recess 21 of the lock, the lock will be held in lock-set position by the piece 9. The piece 9 is held from rotating out of the way of the lock 8 either by the lock 7^a or by a portion of the opposing coupler, as is shown in Fig. 4. When the couplers are pulled apart the lock-set piece 9 by reason of the pressure of the lock on the projection 9^a rotates forwardly until the projection 9^a has freed itself from the re- 80 cess 21 in the lock, as is shown in Fig. 5, and thereupon the lock may drop down into normal or lowermost position, and the lock-set piece 9 will then swing back to its normal position in the head, as is shown in Fig. 1. 85

In the event that the coupler has been accidentally lock-set a brakeman may through the slot in the bottom of the coupler head press upwardly upon the downwardly and rearwardly extending projection 9^b and thus 90 release the piece 9 from engagement with the recess 21 in the lock, thereby allowing the lock to fall to normal position.

Our improved coupler is particularly efficient in operation both in switching and impact coupling, and in the provision which prevents the lock from being accidentally 100

thrown into lock-set position. Impact couplings on fifteen ton cars equipped with couplers embodying our invention have been made satisfactorily up to twelve miles per hour without damaging the couplers and with satisfaction from an operative standpoint.

The terms and expressions which we have employed are used as terms of description 10 and not of limitation, and we have no intention, in the use of such terms and expressions, of excluding any mechanical equivalents of the features shown and described, or portions thereof, but recognize that various structural modifications are possible 15 within the scope of the invention claimed.

What we claim is:

1. In a rigid jawed coupler head having a lock adapted to reciprocate in a cavity 20 thereof; lock actuating means; and a lock-setting mechanism suspended in the cavity arranged to engage and support the lock in elevated position for lock-setting.
2. In a rigid jawed coupler head having a 25 lock adapted to reciprocate in a cavity thereof; lock actuating means; a lock-setting mechanism pivoted in the cavity engaging the lock and suspending it in elevated position for lock-setting.
3. In a rigid jawed coupler head having a 30 lock adapted to reciprocate in a cavity thereof; lock actuating means; a lock-setting member pivotally mounted in the coupler head adapted to have a projection and recess engagement with the lock when actuated by the lock actuating means; and gravity actuated means for causing the lock to return from lock-set to lowermost or locked position.
4. In a rigid jawed coupler head having a 35 lock adapted to reciprocate in a cavity thereof; lock actuating means; a lock-setting member suspended in the cavity and arranged to support the lock in elevated position; and means accessible from without the coupler to disengage said lock-setting member from the lock without the withdrawal of the opposing coupler head.
5. In a rigid jawed coupler head having a 40 lock adapted to reciprocate in a cavity thereof; a lock and a lock-setting member within the coupler head, said lock-setting member being arranged to support the lock in elevated position and adapted to be directly operated from without the coupler and thereby removed from its lock-supporting position while the coupler is engaged by the head of an opposing coupler.
6. In a rigid jawed coupler head having a 45 lock adapted to reciprocate in a cavity thereof; lock actuating means; and a lock-setting mechanism pivoted and operating in the cavity and through the front opening thereof, engaging the lock and suspending it in elevated position for lock-setting,

7. In a rigid jawed coupler head having a lock adapted to reciprocate in a cavity thereof; lock actuating means; and a lock-setting mechanism pivoted and operating in the cavity and through the front opening thereof, the said mechanism being adapted to be lifted by said lock into operative engagement with said lock upon actuation of the lock by the actuating means and by such engagement to support the lock in elevated position for lock-setting. 70

8. In a rigid jawed coupler head having a lock adapted to reciprocate in a cavity thereof; lock actuating means, and a lock-setting mechanism suspended in the cavity having two depending portions, one portion engaging the lock to support it, the other portion being engaged when in lock-set position by a portion of the opposing coupler head. 80

9. In a rigid jawed coupler head having a lock adapted to reciprocate in a cavity thereof; lock actuating means, and a longitudinally extending lock-setting mechanism pivoted in a cavity, the rear end of the mechanism having a slot and projection engagement with an upper portion of the lock to support it, and the forward portion of said mechanism being engaged only when in lock-set position by a portion of the opposing coupler head. 90

10. In a rigid jawed coupler head having a lock adapted to reciprocate in a cavity thereof; lock actuating means; and a lock-setting mechanism mounted within said cavity adapted to engage and suspend the lock in elevated position for the lock-setting, said mechanism being effective only upon actuation by the lock and being in contact with the opposing coupler head only upon operative engagement with the lock. 100

11. In a rigid jawed coupler head having a lock adapted to reciprocate in a cavity thereof; lock actuating means; and lock-setting mechanism mounted within said cavity and having a portion normally lying in the path of movement of a part of said lock, said lock-setting mechanism being actuated by said lock to support said lock in lock-set position and having a projection extending into the forward opening of said cavity for contact with an opposing coupler. 110

12. In a rigid jawed coupler head having a longitudinally extending cavity between such jaws; a lock adapted to reciprocate in the said cavity; and lock actuating means carried by the lock and serving to limit the movement of the lock under buff. 120

13. In a rigid jawed coupler head having a lock adapted to reciprocate in a cavity thereof to assume a projected locking position and a retracted unlocking position; a movable stop carried by the lock to prevent the lock from being driven to its retracted unlocking position under impact coupling. 125

14. In a rigid jawed coupler head having a lock adapted to reciprocate in a cavity thereof; lock actuating means; and a lock-setting mechanism pivoted and operating in the cavity and through the front opening thereof, engaging the lock and suspending it in elevated position for lock-setting, said lock-setting member being held in position to support the lock in lock-set position and being engaged by the said opposing 10 coupler only while in lock-set position.
